UNITED STATES PATENT OFFICE.

DARIUS PARKHURST, OF ST. LOUIS, MISSOURI, ASSIGNOR OF ONE-HALF TO
GEORGE H. KNIGHT, OF SAME PLACE.

HEAD-BLOCK.

SPECIFICATION forming part of Letters Patent No. 274,366, dated March 20, 1883.

Application filed December 5, 1882. (No model.)

To all whom it may concern:

Be it known that I, DARIUS PARKHURST, of the city of St. Louis, in the State of Missouri, have invented a certain new and useful Improvement in Head-Blocks for Saw-Mills, of which the following is a full, clear, and exact description, reference being had to the accompanying drawings, forming part of this specification, and in which—

10 Figure 1 is a top view. Fig. 2 is a side elevation. Fig. 3 is an enlarged top view, and Fig. 4 is a detail view of a modification.

I have shown my invention applied to the head-block for which patent issued to myself 15 and assignee April 25, 1882; but it may be applied to any head-block.

My invention consists in features of novelty pointed out in the claims.

Referring to the drawings, A represents the 20 main shaft, and B the counter-shaft, on the latter of which are the operating parts of the set-works. The shafts are journaled in a suitable frame, C. As my present invention does not relate to the construction of the block in 25 general, it will not be necessary to describe the same.

D represents a scale-wheel rigidly secured to the shaft B, so as to turn with it. The wheel has a circumferential spiral groove, E, 30 which passes around it, say, four or five times, more or less, as required, its face being sufficiently broad therefor. This groove is marked off into sections numbered 1, 2, 3, &c., each numeral representing an inch movement of the 35 knees—that is to say, if the wheel is turned until the figure 2 comes to the position figure 1 had occupied, the knees will have moved back one inch.

F is a finger or pointer, secured by one end 40 to the frame C or to any other suitable object, the other end of which works in the groove E as the wheel turns. Thus, when the finger is at the numeral 1, the knees are one inch back from the saws, and so on. I prefer using a spring-finger which would be rigidly secured to the frame, the spring allowing the finger to remain in the spiral groove as the wheel turns; but instead of the finger springing it may be so secured to the frame or other

object as to move, allowing it to remain in 50 the groove of the wheel. The groove may be marked off into sections of greater or less distance than that shown and described, if desired.

In Fig. 4 is shown a modification of the 55 wheel D, wherein it consists of a band cast upon or secured to the arms of the fly-wheel G on the end of the shaft B. I have made the wheel of such a size that one revolution indicates eight inches movement of the knees, 60 as the figures will show; but this size is not essential.

The operation is as follows: Supposing the last cut of a log has been made, the next thing, of course, to be done is to run the knees 65 back to allow the next log to be rolled onto the carriage against the knees. The sawyer, by glancing at the log, can ascertain very closely its diameter. He then runs the knees back until the desired number on the wheel D 70 comes to the finger—as, for instance, if he judges the log to be two feet in diameter, he turns the wheel D until the numeral 24 came to the finger, or, if he wanted to take, say, a three-inch slab off the log, he would stop 75 the wheel at the numeral 21, and soon; or, instead of the sawyer or operator guessing at the size of the log, its exact diameter may have been ascertained by measuring.

Instead of the wheel D having the spiral 80 groove E, it may have a spiral rib, when the end of the finger F would have a notch to fit over the rib, and the same result would be had.

I am aware that head-blocks have been provided with an indicator-wheel having a spiral 85 groove, and a sliding rod carrying an indicator-finger working in said groove has been before known.

I claim as my invention—

1. The spring-pointer secured to the main 90 frame, in combination with a spirally-grooved indicator-wheel of a head-block for saw-mills, as set forth.

2. In a head-block for saw-mills, a wheel 95 secured to the operating-shaft of the set-works and provided with a spiral groove and scale, in combination with a stationary spring finger or pointer arranged to follow in the groove of

the wheel, substantially as and for the purpose set forth.

3. In a head-block for saw-mills, the combination of frame A, shaft B, wheel D, secured to the shaft B, and having a circumferential spiral groove, E, and a suitable scale, and the spring finger or pointer F, secured by one end

to the frame A and its other end working in the groove E of the wheel D, substantially as and for the purpose set forth.

DARIUS PARKHURST.
